[57] ABSTRACT

A switch enclosure having an openable cover and a handle operable externally of the enclosure for operating a switch therein, is provided with a voidable interlock that normally prevents opening of the cover when the handle is in the switch ON position. The interlock consists of a single screw mounted to the handle and movable therewith. Under normal operating conditions, with the handle in the ON position the screw blocks opening of the cover and in the handle OFF position the screw is aligned with a notch in the cover that provides clearance thereby permitting the cover to be opened. When the handle is in the switch ON position a formation thereof covers the notch so that objects may not be inserted through the notch into the enclosure. Also, when the handle is in ON position, the interlock limits movement of the cover from its fully open position to a partly rather than completely closed position and in this partly closed position it is not possible to apply a padlock to maintain the cover in this position. The head of the screw is accessible externally of the enclosure to permit operation of the screw to a retracted position wherein the interlock is voided and the cover may be opened whether the handle is in switch ON or OFF position.

VOIDABLE COVER INTERLOCK

This invention relates generally to switch enclosures and more particularly relates to an enclosure of this type having novel voidable interlock means that normally prevents the enclosure cover from being opened when the switch is ON.

Many electrical switches, including molded case circuit breakers, are often mounted within a metal enclosure having a separate operating handle mounted on the outside of the enclosure and connected to the handle of the switch inside the enclosure for operating this switch. As a safety feature, under normal conditions an interlock means prevents opening of the enclosure cover when the enclosure mounted handle is in the switch ON position. However, for servicing of the switch it is often necessary to open the enclosure when the handle thereof is in the switch ON position. Thus, the cover interlock must be voidable. Further, the interlock must be so constructed that with the enclosure handle in the switch ON position the enclosure cover cannot be locked in a partially closed position.

Accordingly, the primary object of the instant invention is to provide a novel inexpensive cover interlock for a switch enclosure.

Another object is to provide an interlock of this type that is defeatable.

Still another object of this invention is to provide an interlock of this type including a single screw element threadably mounted directly to the enclosure handle and accessible externally of the enclosure for movement between an operating and a voided position.

A further object is to provide interlock means of this type which, when the enclosure mounted handle is in the switch ON position, limits closing movement of the cover to a position wherein it is not lockable.

These objects as well as other objects of this invention will become readily apparent after reading the following description of the accompanying drawings in which:

FIG. 1 is a front elevation of a switch enclosure constructed in accordance with teachings of the instant invention, with the enclosure cover closed and the enclosure handle in the switch OFF position.

FIG. 2 is a side elevation looking in the direction of arrows 2-2 of FIG. 1.

FIG. 3 is a front elevation of the switch enclosure of FIG. 1 with the enclosure cover pivoted to open position.

FIG. 4 is a view similar to that of FIG. 1 with the enclosure handle in the switch ON position.

FIG. 5 is a side elevation looking in the direction of arrows 5-5 of FIG. 4.

FIG. 6 is a bottom view looking in the direction of arrows 6-6 of FIG. 4.

FIG. 7 is a view similar to that of FIG. 6 with the enclosure cover only partly closed.

FIG. 8 is a perspective of the enclosure mounted switch handle.

Now referring to the Figures, rectangular switch enclosure 11 is provided with openable cover 12 connected thereto at the forward free edge of side wall 11a by side hinges 13, 14. Screws 15, 16 secure insulating block 17 to the rear wall 18 of the closure 11. Insulating block 17 supports three identical switch heads 19a, 19b and 19c, each of a type fully described in U.S. Pat. No. 3,259,723 issued July 5, 1966 to R.S. Davis for an Electric Switch Head. Each switch head 19a, 19b, 19c

is connected in electrical series with an individual cartridge fuse 21, also mounted to insulating block 17.

All three switches 19a, 19b, 19c are connected to the offset portion 22 of operating bail 23 whose ends are connected at pivots 24, 25 to side walls 11a, 11b, respectively, of enclosure 11. Over center torsion spring 26 is anchored at one end thereof to enclosure side wall 11a by pin 27 and the other end 28 of torsion spring 26 is wound about offset portion 22 of bail 23. The end of bail 23 mounted to pivot 25 is provided with elongated flattened formation 29 having apertures (not shown) on opposite sides of pivot 25 to receive formations 31, 32 which project inward from support section 33 of enclosure operating handle 30 to provide a good driving connection between handle 30 and bail 23.

Support section 33 of handle 30 is disposed adjacent the inner surface of enclosure side wall 11b with curved operating portion 34 of handle 30, which is at right angles to handle portion 33, being disposed slightly forward of the forward edge of side wall 11b and extending thereover. Handle support section 33 also includes clearance aperture 36 for bail pivot 25 and rear notch 37 which cooperates with ear 68 struck from side wall 11b, to limit pivotal movement of enclosure handle 30.

The rear end 41 of cover catch 40 is welded to side wall 11b near the upper end thereof and includes deflectable locking portion 42 which extends forward of the forward edge of enclosure side wall 11b and is provided with aperture 43 to receive the shackle of a padlock (not shown). With cover 12 fully closed, locking section 42 protrudes through cover slot 44 so that a padlock (not shown) connected at aperture 43 will lock cover 12 closed. Handle 30 is provided with elongated slots 38, 39 that are accessible when handle 30 is in its respective ON and OFF switch positions to receive padlocks for locking handle 30 in these respective positions.

Interlock screw 50 is threadably mounted to handle 40 supports portion 33 at a position slightly forward of locking slot 39. Screw head 51 is accessible externally of enclosure 11 to back screw 50 from its operating position shown in the drawings to a voided position wherein the free end 52 of screw 50 is flush with handle 45 support section surface 53, for a reason to be hereinafter explained. The free end of interlock screw 50 is slightly enlarged or the end threads are staked so that screw 50 may not be dismounted from handle 30.

Cover 12 is provided with notch 55 along the edge thereof remote from hinges 13, 14 to provide clearance for handle 30 and is provided with an interlock cut-out or notch 56 that is aligned with and provides clearance for the body of interlock screw 50 when enclosure handle 30 is in its switch OFF position of FIG. 1. When handle 30 is in its switch ON position, formation 54 extending inward from handle support section 33 is disposed immediately behind interlock notch 56 to effectively close the latter against insertion of foreign objects into enclosure 11.

As seen in FIG. 4, when handle 30 is in its switch ON position the body of interlock screw 50 is out of alignment with interlock notch 56 in cover 12 thereby blocking movement of cover 12 to its open position. However, for purposes of servicing the electrical device within enclosure 11, cover 12 may be opened after handle 30 is operated to the switch ON position by merely backing interlock screw 50 to the right with respect to

FIG. 6 so that the body of screw 50 will not block movement of cover 12.

For those situations in which handle 30 is operated to the switch ON position after cover 12 is open, interlock screw 50 in its operating position (shown) will prevent cover 12 from moving to a fully closed position so long as handle 30 remains in switch ON position. Under these circumstances interlock screw 50 will limit movement of cover 12 to a partially closed position and in this partially closed position cover catch aperture 43 is, for the most part, disposed behind the front wall of cover 12 so that aperture 43 is inaccessible to receive the shackle of a padlock.

Thus, it is seen that the instant invention provides a very inexpensive construction for a voidable cover interlock for a switch enclosure. In particular, such voidable interlock consists of a retractable screw mounted to the enclosure handle and positioned to cooperate with a cover notch which permits opening of the cover when the handle is in switch OFF position. However when the handle is in switch ON position the interlock screw is so positioned that it blocks opening of the cover.

Although the invention has been described above with respect to its preferred embodiments, it will be understood that many variations and modifications will be obvious to those skilled in the art. It is preferred, therefore, that the scope of the invention be limited not by the specific disclosure herein but only by the appended claims.

The embodiments of the invention in which an exclusive privilege or property is claimed are defined as follows:

1. In combination, an enclosure for a switching device; an openable cover for said enclosure; an operating handle mounted to said enclosure and movable between a first and a second position to operate a switching device within said enclosure to its respective closed and open positions; voidable interlock means operated to third and fourth positions by operation of said handle to said first and second positions, respectively; said interlock means when in said third position blocking opening of said cover and when in said fourth position permitting opening of said cover; when said handle is in said first position and said cover is closed, said interlock means being accessible from outside of said enclosure for movement of said interlock means from an operating position to a voided position; said interlock means being comprised of a cover blocking element mounted to said handle; with said cover closed, said handle in said first position and said interlock means in

said operating position, said element being positioned in front of said cover.

2. A combination as set forth in claim 1 also including additional means operative when said cover is fully closed to receive a lock for holding said cover in closed position; with said cover open, said handle in said first position, and said interlock means in said operating position, said interlock means preventing closing of said cover beyond a partially closed position wherein said additional means is inaccessible for reception of a padlock.

3. A combination as set forth in claim 2 in which the additional means includes a cover catch element secured to said enclosure and extending forward thereof, said cover having an aperture to receive said cover catch element, said cover catch element having a lock receiving aperture positioned in front of said cover when the latter is closed and behind said cover when the latter is in said partially closed position.

4. A combination as set forth in claim 1 in which said element is withdrawn from in front of the cover, when said interlock means is in said voided position, by being repositioned relative to said handle.

5. A combination as set forth in claim 4 in which the cover includes a clearance notch aligned with said element to permit opening of said cover when said handle is in said second position.

6. A combination as set forth in claim 5 in which said handle includes an offset formation within said enclosure constructed and positioned in alignment with said clearance notch to block entry of objects into said enclosure through clearance notch when said handle is in said first position.

7. Apparatus as set forth in claim 6 in which the element is a screw threadably mounted to said handle.

8. Apparatus as set forth in claim 5 in which the enclosure includes a rear wall confronting said cover when the latter is in closed position, and side walls extending forward from said rear wall; said handle being mounted on a pivot at one of said side walls.

9. Apparatus as set forth in claim 8 in which said handle includes first and second sections extending in opposite directions from said pivot, with said handle in said first position, said first section extending forward of said enclosure and being depressible for operation of said handle to said second position; with said handle in said second position, said second section extending forward of said enclosure and being depressible for operation of said handle to said first position.
